United States Patent Office

Des. 185,328
Patented May 26, 1959

185,328

TEXTILE FABRIC OR SIMILAR ARTICLE

William Stark, New York, N.Y., assignor to Aileen Mills
Company, Biscoe, N.C., a corporation of Delaware

Application November 13, 1958, Serial No. 53,371

Term of patent 14 years

(Cl. D92—1)

FIG. 1.

FIG. 2.

I claim:

The ornamental design for a textile fabric or similar article, substantially as shown.
